UNITED STATES PATENT OFFICE.

CHARLES C. GLADWIN, OF NEW YORK, N. Y.

PUNCHING-TOOL.

1,147,284.

Specification of Letters Patent Patented July 20, 1915.

Application filed February 1, 1915. Serial No. 5,470.

To all whom it may concern:

Be it known that I, CHARLES C. GLADWIN, a citizen of the United States of America, residing at Manhattan borough, county of New York, State of New York, have invented certain new and useful Improvements in Punching-Tools, of which the following is a full, clear, and exact description.

This invention relates to an improvement 13 in punches, the object being to provide a punch arranged so that it can be used as a hand or bench punch; that is to say, held in the hands while punching, or secured to a bench, the punch being arranged for both 15 uses.

One of the objects of my invention is to provide a punch or punch holder, provided with a punching tool that is removably supported, and also provided with depth and 20 edge gages.

Further features of my improvement consist of strippers, by which means the metal is readily stripped from the tool.

Other advantageous structural improvements will also be hereinafter described.

I will now proceed to describe my invention in detail, the novel features of which I will point out in the appended claim, reference being had to the accompanying drawing, forming part hereof, wherein—

Figure 1 is a vertical sectional view of my improved punch, the handle being broken off; Fig. 2 is a sectional plan view thereof, the section being taken on a line 2—2 in Fig. 35 1 and not showing the strippers 26 herein-after described; Fig. 3 is a sectional plan view, the section being taken on a line 3—3 in Fig. 1, the edge gage stops being omitted; and Fig. 4 is a sectional plan view of the 40 punch-holder, the section being taken on a line 4—4 in Fig. 1.

As herein arranged my improved device consists of a holder 1 having a handle 2 and brackets 3, the handle being used when the 45 device is used for overhead work, in which position the device will have to be held by one hand and the punch manipulated by the other. By means of the brackets 3 and screws or bolts, the device can be secured to 50 a bench for bench punching. The holder 1 is provided with a jaw 4 into which the material to be punched is placed. The bottom portion of the holder 1 carries a die 5 which co-operates with a tool or punch 6 carried 55 by a tool-holder or stock 7 which in turn is carried by that portion of the holder above

the jaw 4 which I will term the head, and indicate said head by the numeral 8. That portion of the holder which carries the die 5 I will term the base and designate it by the 60 numeral 9. It will be seen that the punch 6 is provided near its end with a countersinking portion (Fig. 1). This combination of punch and countersink has the advantage of both punching a hole and countersinking in 65 one operation.

The tool stock 7 consists of a threaded spindle which engages the threads 10 in the head 8. When the stock 7 is rotated it will move longitudinally inward or outward in 70 this head 8 in accordance with the direction of rotation; hence, the punch 6 will be caused to move toward the die 5 or away therefrom. The tool or punch 6 is removably supported by the stock 7 and is provided with a head 11 75 fitting a counterbore 12 in the head 13 of the stock 7, the said head 13 being square or hexagonal to receive a socket wrench. To hold the tool against longitudinal movement within the stock 7 I provide the counterbore 80 12 with threads to receive a threaded abutment stud 14 which when screwed home will be jammed against the head 11 of the tool 6. To prevent the tool from rotating within the stock I provide the head 11 of the tool 6 85 with a vertically arranged recess or groove 15 engaged by the tapered inner end of a set-screw 16.

Upon the threaded shank of the holder 7 I mount a rotatable threaded collar 17 which 90 constitutes a depth gage and limits the downward movement of the stock 7. By manipulating the gage or collar 17 I am able to control the movement of the punch, that is to say, the downward movement. 95

A further feature of my improvement consists of the die 5 which is provided with an annular groove 18 which is V-shaped in cross section. A set-screw 19 holds the die in its seat or socket 20. By means of the annular recess 18 I am able to quickly secure the die in place, there being no holes to be alined before the set-screw can be set up. Said annular recess or groove 18 is adapted to receive the end of said screw in an angle, 100 in order that said die may be held securely. 105

To control the distance that a hole is to be made from the edge of the material, I provide adjustable stops 21 carried by graduated plates 22. The stops 21 are provided with slots 23 through which set-screws 24 pass into brackets 24^a on the holder 1. The 110

forward end of each gage or plate 22 is secured by a set-screw 23, passing through lateral lugs 25^a of the holder 1, said lugs being perforated and indicated by dotted lines on Fig. 2.

At each side of the holder 1 I place adjustable stops (in this instance threaded spindles 26) which act as strippers for thick material. When the material is placed in the jaw 4 the stops or strippers 26 will be manipulated to rest thereupon. After the hole is punched and the tool is being withdrawn, the strippers 26 act to hold the material down, so that the tool can be readily withdrawn. For thin material I employ a stripper 27 in the form of a bifurcated block, the opening 28 therein being but a little wider than the diameter of the punch 6. When the punch is to be withdrawn from thin material, I place the stripper 27 in the mouth or jaw 4 between the upper wall thereof and the material, the tool passing through the opening 28. When the tool is withdrawn the stripper 27 will hold the material while the punch is being moved upwardly. To manipulate the punch I place a socket wrench upon the head 13 of the stock 7.

A further feature of improvement consists of a sight 29, which is a pointed projection carried by the head 8 in alinement with the

axis of the tool 6 as shown in Fig. 3 and with the central longitudinal line of the holder 2. This pointed forward projecting sight is preferably integral with said head. ³⁵ Like said head, the sight is necessarily fixed in its position with respect to said jaw and die. Should I desire to punch a hole upon a given line the sight 29 enables me to accurately position the line relative to the punch. ⁴⁰ If desirable the stripper 27 can be attached to the holder by a chain 30.

Having now described my invention, what I claim and desire to secure by Letters Patent is:

In combination with a screw-tapped holder, an externally screw-threaded tool-stock engaging said holder for longitudinal adjustment and provided with a longitudinal central bore, a tool set into said bore, means for locking said tool in said stock and a collar screwed on said stock above said holder and constituting an adjustable stop which limits the movement of said stock and tool through the holder. ⁵⁰ ⁵⁵

Signed at New York city, N. Y., this 30 day of January, 1915.

CHARLES C. GLADWIN.
